UNITED STATES PATENT OFFICE

CHARLES E. DAVIS, OF DAVENPORT, FLORIDA, ASSIGNOR TO GOODMAN MANUFACTURING COMPANY, OF CHICAGO, ILLINOIS, A CORPORATION OF ILLINOIS

MOBILE MACHINE

Original application filed August 5, 1926, Serial No. 127,301. Divided and this application filed November 5, 1927. Serial No. 231,228.

This invention relates particularly to power shovels for use in confined spaces, such as in mines, although not limited to this use alone.

5 One of the objects of the invention resides in providing a machine, adapted for propulsion, which may be turned abruptly or have its direction of propulsion changed within a relatively small space with obvious advantage particularly as relates to underground power shovels.

Other objects reside in the provision of a machine of the above character with a view toward compactness, effective operation and 15 proper control.

Referring now to the drawings:

Figure 1 is a top plan view of a power shovel embodying one form of my invention, with parts broken away and in section and 23 intermediately broken and longitudinally condensed;

Figure 2 is a side elevation of the machine illustrated in Figure 1 with parts broken away and in section;

25 Figure 3 is a side elevation of the machine illustrated in Figure 1 showing the side of the machine opposite that which is shown in Figure 2 and with parts broken away and in section;

30 Figure 4 is a transverse vertical sectional view of the main portion of the machine on the line 4—4 of Figure 1 and with one of the continuous tread mechanisms in elevation and partially broken away and with the other 35 continuous tread mechanism in transverse section;

Figure 5 is a diagrammatic view of the machine showing a part thereof in a different position than that in which it is shown in 40 Figures 2 and 4; and

Figure 6 is a partial section on line 6—6 of Figure 1.

Like numerals refer to like parts throughout the several figures.

45 In the drawings 1 designates a base frame which is carried on laterally spaced continuous tread devices 2 of usual construction which are adapted for the propulsion of the shovel.

50 The base frame 1 is provided with a cen-

trally disposed concentrically bored vertical hub 3 extending upwardly therefrom. A turntable or rotatable frame 4 is carried on the base frame and is journaled on said hub 3 for angular movement in a horizontal plane 55 with respect to the base by means of a bored hub 5 formed integrally with the turntable and extending upwardly therefrom and journaled on the hub 3 of the base and a stepped hub of a gear 6 secured on an intermediate 60 portion of the hub 3, the web of this gear forming a downward thrust bearing for the turntable and a ring 7 screwthreaded on the upper end of the hub 3 forming an upward thrust bearing for the turntable. See particularly Figure 4.

A transversely disposed horizontal shaft 8 is rotatably mounted on the rear end of the turntable 4, and journaled on this shaft and extending forwardly therefrom are two elevating frames 9 and 10 comprising pairs of arms. These arms of each of these frames are disposed on respective sides of the hubs 3 and 5 of the base frame 1 and the turntable 4 respectively, and a scoop beam 11 comprising 75 laterally spaced parallel channel members 12 has these channel members mounted for longitudinal movement on respective arms of the inner elevating frame 9. A forwardly facing scoop 13 is carried on the front end of the beam 11. A reaction beam 15 comprising laterally spaced parallel members 16 has these members mounted for longitudinal movement on respective arms of the outer elevating frame 10.

85 The operation of the beams 11 and 15 or the detailed structure relating thereto requires no further description for the present purposes, they being fully described and features thereof claimed in my co-pending 90 application, Serial No. 127,301, filed August 5, 1926, for improvements in power shovels, of which the present application is a division.

95 Mounted on the elevating frame 9 adjacent its rear and above the beam 11 is an electric motor 21, and this motor drives, by means of a reducing gear train 22, a horizontal transversely disposed shaft 23 journaled on the top of the frame 9 and on lateral 100

extensions 24 of the frame 9 extending outwardly below the respective arms of the frame 10 and upwardly for journaling respective ends of the shaft 23. See Figures 1 and 6.

5 The motor 21 is utilized for selectively operating the beams 11 and 15 and related devices by means of manually controlled driving devices connected with the shaft 23 in a 10 manner unnecessary to be described for the present purposes.

Mounted on the right hand portion of the shaft 23 between the frame 9 and the right hand extension 24 thereof is a pair of manually controlled releasable frictional drive devices 61 of the planetary type, which are connected to drive a horizontal transversely disposed shaft 62 journaled in an extension 63 of the elevating frame 9 adjacent its rear 20 end by means of two reducing gear trains 64, one of which gear trains includes an additional idler gear 65 whereby the shaft 62 is driven in respective directions by the driving devices 61. See Figures 1 and 6.

25 The frames 9 and 10 are journaled for pivotal movement in a vertical plane on the transmission shaft 8 which is journaled on brackets 27 extending rearwardly from the turntable 4. Secured on the shaft 8 is a 30 gear 82 which meshes with the gear of one of the gear trains 64 secured to the shaft 62. See Figures 1 and 3. Thus the shaft 8 may be driven in either direction from the motor 21 by means of the driving devices 61 and 35 the gear trains 64 in a manner that permits pivotal movement of the elevating frame 9 with respect to the turntable.

The turntable 4 is operated angularly about its vertical axis by the motor 21 and 40 through the shaft 8 in the following manner. See Figures 1 and 2. A shaft 83 is journaled on the rear portion of the turntable and is disposed radially with respect thereto. Secured on the rear end of the shaft 83 is a 45 bevel gear 84 which meshes with a bevel gear 85 secured on the shaft 8, whereby the shaft 83 is driven from the shaft 8. The hereinbefore mentioned gear 6 is an upwardly facing bevel gear, and journaled on the turntable and on the front end of the shaft 83 is a bevel gear 86 which meshes with the gear 6. The gear 86 is driven from the shaft 83 by 50 means of a manually controlled releasable positive clutch 87 of usual construction. Thus, assuming the clutch 87 is engaged, the turntable may be operated in either direction by the motor 21 by manipulation of the driving devices 61.

The continuous tread devices 2 are operated 55 for the propulsion of the machine by the motor 21 and through the shaft 8 in the following manner; See Figures 1, 2 and 5. Journaled for rotation on the hub 3 of the base frame 1 between the main portion of the base frame and the hereinbefore men-

tioned gear 6 is a large bevel gear 89 having both upwardly and downwardly facing teeth. A horizontal transversely disposed shaft 90 is journaled on one side of the turntable 4 on an axis intersecting the axis of the turntable, and a bevel gear 91 is secured on this shaft and meshes with the upwardly facing gear teeth of the gear 89. Two aligned sprockets 92 are secured respectively on the shafts 90 and 8, and a chain 93, see 70 Figures 1 and 5, is trained over these sprockets for driving the shaft 90 from the shaft 8 and through the gear 91 driving the gear 89. A horizontal transversely disposed shaft 94, disposed radially of the gear 89, is journaled on the base frame 1 at one side thereof, and a bevel gear 95 is secured on this shaft and meshes with the downwardly facing gear teeth of the gear 89. A sprocket 96 is secured on the shaft 94 and a second sprocket 97 is rotatably mounted in alignment with the sprocket 96 on a driving shaft 98 of the continuous tread devices 2. A chain 99 is trained over the sprockets 96 and 95 80 for driving the sprocket 97 from the gear 89, and a manually controlled releasable positive clutch 100 of the usual construction fixes the sprocket 97 with the shaft 98 for driving the continuous tread devices 2 from the motor 21. Thus, assuming the clutch 100 is engaged, the continuous tread devices 2 may be operated in either direction from the motor 21 by manipulation of the driving devices 61.

A means is provided whereby the machine 100 may be turned abruptly or have its direction of propulsion changed within a relatively small space and consists of the following: See Figures 4 and 5. A centrally disposed support member 102 is disposed underneath the base frame 1 between the continuous tread devices 2 and is engageable with the supporting floor for carrying the machine. This support member is provided with a centrally disposed vertical shaft 103 extending 105 upwardly therefrom through and journaled in the bore of the hereinbefore described hub 3 of the base frame 1. A bevel gear 104, disposed underneath the base frame 1 and rotatably mounted thereon by means of a suitable bearing 105, is screwthreaded upon the lower portion of the shaft 103 so that rotation of this gear with respect to this shaft effects relative vertical adjustment between the support member 102 and the base frame 1 110 carrying the continuous tread devices.

When it is desired to turn the machine the support member 102 is operated downwardly by rotation of the gear 104 in the proper direction until the support member engages 115 with the supporting floor and lifts the base frame 1 to a position in which the continuous tread devices 2 are disengaged with the supporting floor, as shown in Figure 5, in which position the base frame 1 may be 120

5 moved angularly about the support member and shaft to any desired angular position. After the base frame 1 is positioned the bevel gear 104 is operated in the opposite direction to again engage the continuous tread devices 2 with the supporting floor and to disengage the support member 102 from the supporting floor and to return it to its normal position elevated from the supporting floor 10 as shown in Figure 4.

10 The bevel gear 104 is operated and the base frame 1 is operated angularly with respect to the support member 102 from the motor 21 in the following manner:

15 The gear 89 is driven from the shaft 8 in the manner hereinbefore described, the shaft 8 being driven in either direction from the motor 21 through the driving devices 61 and gear trains 64. A horizontal shaft 106 20 is journaled on the base frame 1 at the front thereof on an axis intersecting the axis of the turntable 4 and shaft 103. Secured on this shaft 106 is a bevel gear 107 which meshes with the bevel gear 104 for driving the same. 25 Journaled on the shaft 106 is another bevel gear 108 which meshes with the downwardly facing teeth of the hereinbefore mentioned gear 89, and a manually controlled releasable positive clutch 109 of usual construction 30 fixes the gear 108 with the shaft 106 for driving the gear 104 for vertically adjusting the support member 102. Thus, assuming the clutch 109 is engaged the bevel gear 104 may 35 be operated in either direction from the motor 21 by manipulation of the driving devices 61.

40 In order to prevent angular movement of the turntable 4 by reason of reaction caused in the driving of the continuous tread mechanisms 2 a removable stud 111 is engaged in 45 registering radial bores in the hubs 3 and 5 respectively of the base frame 1 and turntable 4, it being obvious that this stud is removed when it is desired to operate the turntable on the base frame or vice versa as when shoveling and when turning the base on the support member 102. See particularly Figure 3.

50 The upper end of the hub 5 of the turntable has clutch teeth 112 formed thereon, and a clutch member 113 is mounted for sliding movement on the shaft 103 above the hub 3 of the base frame 1. See Figures 1, 3 and 4. A key 114 is secured in a keyway 55 of this clutch member and is slidably engaged in a keyway 115 on the shaft 103 to rotatably fix this clutch member and shaft. The lower end of this keyway engaging the key 114 limits downward movement of the clutch member 113 with respect to the shaft 103 so that when the support member 102 is in 60 its normal upper position, as shown in Figure 4, the clutch member 113 is disengaged from the turntable thereby permitting the 65 turntable to turn independently of the sup-

port member 102 and shaft 103. The hub of the clutch member 113 is provided with a radial bore 116 for the insertion of a removable bar, indicated by dotted line at 117 in Figure 3, for preventing rotation of the 70 shaft 103 when the gear 104 is operated when the clutch member 113 is disengaged from the clutch teeth 112.

75 The clutch member 113 is engaged with the clutch teeth 112 when the support member 102 is in a lower position with respect to the turntable and carrying the machine for the turntable of the base frame 1, as shown in Figure 5. When the machine is so carried by the support member the base frame 1 and with it the continuous tread devices 2 may be turned about the support member by engagement of the clutch 87 and manipulation of the driving devices 61. The clutch member 113 engaged with the clutch teeth 112 80 provides for the reaction on the turntable caused by the turning of the base frame 1 by fixing the turntable with the support member 102 engaged on the supporting floor. The clutch member 113 engaged with the clutch 90 teeth 112 also provides for the reaction of the operation of the gear 104.

95 While I have herein shown and described one form of my invention, I do not wish to be limited to the precise details of construction or arrangement of parts herein shown and described except as specifically limited in the appended claims.

I claim as my invention:

1. In a machine of the character described, 100 the combination of a base, a pair of laterally spaced continuous tread propulsion means mounted on said base and carrying the same, a centrally disposed support member between said propulsion devices and engageable with a floor for carrying said base and with respect to which said base is angularly movable on a centrally disposed vertical axis, a revoluble gear disposed on said axis for vertically adjusting said support member with respect to said base for alternate engagement of said propulsion means and said support member with the floor, a power operated revoluble gear disposed on said axis, a third gear rotatably mounted on said base and meshing 105 with said second mentioned gear, releasable clutch means for driving said propulsion devices from said third gear, a fourth gear rotatably mounted on said base and meshing with said second mentioned gear, a fifth gear 110 rotatably mounted on said base and meshing with said first mentioned gear, and a second releasable clutch means for driving said fifth gear from said fourth gear.

115 2. In a power shovel, the combination of 125 a base frame, propulsion means carrying said base frame for propulsion, a turntable mounted on said base frame for movement in a horizontal plane, a gear disposed coaxially with said turntable and secured with said 130

base frame, a second gear rotatably mounted on said turntable and meshing with said first mentioned gear for operating said turntable, a third gear rotatably mounted and disposed coaxially with said turntable, a fourth gear rotatably mounted on said turntable and meshing with said third gear for driving the same, and a fifth gear rotatably mounted on said base frame and meshing with said third gear for driving said propulsion means.

3. In a power shovel, the combination of a base frame provided with a centrally disposed hub extending upwardly therefrom, propulsion means carrying said base frame for propulsion, a turntable above said base frame and journaled about said hub for angular movement, a gear disposed coaxially with and secured on said hub below said turntable, a second gear rotatably mounted on said turntable and meshing with said first mentioned gear for operating said turntable, a third gear journaled on said hub below said first mentioned gear, a fourth gear rotatably mounted on said turntable and meshing with said third gear for driving the same, and a fifth gear rotatably mounted on said base frame and meshing with said third gear for driving said propulsion means therefrom.

4. In a power shovel, the combination of a base frame provided with a centrally disposed hub extending upwardly therefrom, propulsion means carrying said base frame for propulsion, a turntable above said base and journaled about said hub for angular movement, an upwardly facing bevel gear disposed coaxially with and secured on said hub below said turntable, a second bevel gear rotatably mounted on said turntable and meshing with said first mentioned gear for operating said turntable, a third bevel gear larger than said first mentioned gear and provided with upwardly and downwardly facing teeth and journaled on said hub below said first mentioned gear, a fourth bevel gear rotatably mounted on said turntable and meshing with the upwardly facing teeth of said third gear for driving the same, and a fifth gear rotatably mounted on said base frame and meshing with the downwardly facing teeth of said third gear for driving said propulsion means therefrom.

Signed at Chicago, in the county of Cook and State of Illinois, this 1st day of November, A. D. 1926.

CHARLES E. DAVIS.
